CLAIM

The ornamental design for a bracket, as shown and described.

DESCRIPTION

FIG. 1 is a perspective view of the bracket showing our new design;

FIG. 2 is a front view thereof;

FIG. 3 is a back view thereof;

FIG. 4 is a right side view thereof, the left side view being a minor image thereof, therefore not shown; and,

FIG. 5 is a top view thereof.

The broken lines are included for the purpose of illustrating environment and form no part of the claimed design.

1 Claim, 5 Drawing Sheets(56)
